UNITED STATES PATENT OFFICE.

JOSEPH GALLINGER, OF NEW YORK, N. Y.

DESIGN FOR A LAMP-PEDESTAL.

SPECIFICATION forming part of Design No. 17,278, dated April 26, 1867.

Application filed March 19, 1867. Serial No. 231,606. Term of patent 3½ years.

To all whom it may concern:

Be it known that I, JOSEPH GALLINGER, a citizen of the United States, residing at New York, in the county of New York and State of New York, have invented and produced a new and original Design for Lamp-Pedestals, of which the following is a specification.

This design has for its object to provide a novel lamp-pedestal; and it is illustrated by the accompanying drawing, in which the figure is a side elevation of the pedestal and fount.

In the drawing, the letter A indicates the base-piece, having a projection, B, surmounted by a rugged projection, B'.

The letter C indicates a figure in representation of an elephant with its trunk hanging down and its feet D and lower portion of its body arranged on the rugged part B' of the

projection B, said rugged part extending up between the feet. On the back of the figure 20 of the elephant is the representation of a howdah, E, surmounted by a projection, F, and a lamp-fount, G.

Having thus described my invention, what I claim is—

The design for a lamp-pedestal, consisting of the base A, the projection B, the figure, C, of an elephant, the howdah E, and a projection, F, rising from the howdah, substantially as shown and described.

In testimony whereof I affix my signature in presence of two witnesses.

JOSEPH GALLINGER.
